CONDENSER FOR INTERNAL-COMBUSTION ENGINES

Application filed April 13, 1926. Serial No. 101,724.

The object of our invention is to provide a condenser applicable for use in steam cooling systems for internal combustion engines, said condenser comprising juxtaposed direct and 5 reflux condensing units of novel construction and arrangement, and simple and inexpensive to manufacture.

A practical embodiment of our invention is represented in the accompanying drawings, 10 in which

Fig. 1 represents the condenser in longitudinal vertical section, taken in the plane of the valved connection between the two condensing units.

Fig. 2 represents a detail vertical longitudinal section, taken in another plane.

The condenser herein shown comprises juxtaposed direct and reflux condensing units having separate upper chambers and 20 separate lower chambers, the lower chambers being connected by a passage which is preferably valved.

The direct condensing unit of the condenser is herein shown as comprising passages 1 connecting upper and lower chambers 2 and 3, the upper chamber 2 having a steam inlet port 4.

The reflux condensing unit of the condenser is located immediately in front of the direct condensing unit and it is herein shown as comprising passages 5 connecting upper and lower chambers 6 and 7, the upper chamber 6 having a removable filling cap 8 and also a vent 9 to external atmosphere. The lower chamber 7 is provided with a discharge port 10 for the water of condensation. A water overflow passage 11 may be provided for the chamber 7 so that a specified quantity of water may be supplied to the system when 35 desired, the chamber end of which passage is normally water sealed so that the steam will be caused to pass upwardly through the reflux condensing unit rather than permitted to escape through the said overflow passage.

A passage leads from the lower chamber 3 of the direct condensing unit to the lower chamber 7 of the reflux condensing unit. In the present instance this passage is shown as valved and as constructed as follows:

A hollow plug has its closed lower end 13

screwed into the bottom of the hollow casing which encloses the two lower chambers 3 and 7. A valve cage 14 is screwed into the open upper end of the said hollow plug, which cage has a port 15 normally closed by a ball valve 16. The side wall of the hollow plug has a port 17 opening to the lower chamber 3 of the direct condensing unit. From the above description it will be seen that the plug and valve may be readily removed, when so desired.

A drain cock 18 may be provided for the lower chamber 3 of the direct condensing unit and a drain passage 19 and cock 20 may be provided for the lower chamber 7 of the reflux condensing unit and the valve cage 14.

In the present instance a single hollow casing 21 is provided with a partition 22 to form the upper chambers 2 and 6 of the direct and reflux condensing units, and a single L-shaped hollow casing 23 is provided with a partition 24 to form the two chambers 3 and 7 of the direct and reflux condensing units.

In operation:—The steam entering the upper chamber 2 of the direct condensing unit is more or less condensed in the passages 1, the water of condensation gathering in the lower chamber 3. The water of condensation passes upwardly from the lower chamber 3 into the lower chamber 7 of the reflux condensing unit where it may be drawn off through the passage 10. If more steam is being generated than can be condensed in the direct condensing unit, it will pass upwardly from the chamber 3 into the chamber 7 through the water therein (which will assist in the condensation of the steam) and from thence upwardly through the passages 5 into the upper chamber 6 where such steam as has not been condensed in the reflux condensing unit will escape to external atmosphere through the vent 9. It will be understood that this reflux condensing unit is arranged in the coldest part of the system in front of the direct condensing unit so that the greatest practicable amount of steam will condense and join the water of condensation in the lower chamber 7.

It will be understood that the passages 1 and 5 of the two condensing units may be of any well known or approved form.

Where a specified quantity of water is required to be supplied to the system, the overflow passage 11 is provided, the end of which passage which is located in the chamber 7 being arranged to be normally sealed by the water in said chamber so that the steam will be caused to pass upwardly through the reflux condensing unit. With other systems, the overflow passage may be omitted, the vent 9 being sufficient for the outward passage of the air during the heating period and for its return during the cooling period.

While describing this condenser as adapted to receive water it is to be understood that any suitable liquid may be utilized.

It is evident that various changes may be resorted to in the construction, form and arrangement of the several parts without departing from the spirit and scope of our invention; hence, we do not intend to be limited to the particular embodiment herein shown and described, but

What we claim is:

1. An air cooled steam condenser comprising a direct condensing unit having connected upper and lower chambers and a reflux condensing unit having connected upper and lower chambers, the reflux condensing unit being located in proximity to the direct condensing unit, the upper chamber of the direct condensing unit having a steam inlet port and the lower chamber of the reflux condensing unit having a water discharge port and a restricted passage for the escape of the water of condensation from the lower chamber of the direct condensing unit into the lower chamber of the reflux condensing unit.

2. An air cooled steam condenser comprising a direct condensing unit having connected upper and lower chambers and a reflux condensing unit having connected upper and lower chambers, the reflux condensing unit being located in proximity to the direct condensing unit, the upper chamber of the direct condensing unit having a steam inlet port and the lower chamber of the reflux condensing unit having a water discharge port and a restricted passage for the escape of the water of condensation from the lower chamber of the direct condensing unit into the lower chamber of the reflux condensing unit, and a valve in said normally closed restricted passage for preventing the return of the water into the lower chamber of the direct condensing unit.

3. An air cooled steam condenser comprising a direct condensing unit having connected upper and lower chambers and a reflux condensing unit having connected upper and lower chambers, the reflux condensing unit being located in proximity to the direct condensing unit, the upper chamber of the direct condensing unit having a steam inlet port and the lower chamber of the reflux condens-

ing unit having a water discharge port and a restricted passage for the escape of the water of condensation from the lower chamber of the direct condensing unit into the lower chamber of the reflux condensing unit, a valve in said normally closed restricted passage for preventing the return of the water into the lower chamber of the direct condensing unit, and a vent to external atmosphere from the upper chamber of the reflux condensing unit.

4. An air cooled steam condenser comprising a direct condensing unit having connected upper and lower chambers and a reflux condensing unit having connected upper and lower chambers, the reflux condensing unit being located in proximity to the direct condensing unit, the upper chamber of the direct condensing unit having a steam inlet port and the lower chamber of the reflux condensing unit having a water discharge port and a restricted passage for the escape of the water of condensation from the lower chamber of the direct condensing unit into the lower chamber of the reflux condensing unit, a valve in said normally closed restricted passage for preventing the return of the water into the lower chamber of the direct condensing unit, a vent to external atmosphere from the upper chamber of the reflux condensing unit, and a water overflow passage for the lower chamber of the reflux condensing unit, the overflow end of which is at a higher level than said lower chamber of the reflux condensing unit and the chamber end of such passage is normally water sealed to that the steam is caused to pass upwardly through the reflux condensing unit.

5. An air cooled steam condenser comprising a direct condensing unit having connected upper and lower chambers and a reflux condensing unit having connected upper and lower chambers, the reflux condensing unit being located in proximity to the direct condensing unit, the upper chamber of the direct condensing unit having a steam inlet port and the lower chamber of the reflux condensing unit having a water discharge port and a restricted passage for the escape of the water of condensation from the lower chamber of the direct condensing unit into the lower chamber of the reflux condensing unit, a valve in said normally closed restricted passage for preventing the return of the water into the lower chamber of the direct condensing unit, a vent to external atmosphere from the upper chamber of the reflux condensing unit, a water overflow passage for the lower chamber of the reflux condensing unit, the overflow end of which is at a higher level than said lower chamber of the reflux condensing unit and the chamber end of such passage is normally water sealed so that the steam is caused to pass upwardly through the reflux condensing unit.

condensing unit, and a water filling opening for the upper chamber of the reflux condensing unit.

In testimony that we claim the foregoing as our joint invention, we have signed our names this 30th day of March, 1926.
